J. DERK

VALANCE FOR WINDOW DRAPERIES OR SIMILAR ARTICLE

Filed Nov. 29, 1926

INVENTOR:

Joseph Derk,

BY

Wm. Sherry & Farbanks

ATTORNEYS.

UNITED STATES PATENT OFFICE.

JOSEPH DERK, OF PHILADELPHIA, PENNSYLVANIA, ASSIGNOR TO THE DERK MANUFACTURING COMPANY, OF PHILADELPHIA, PENNSYLVANIA, A CORPORATION OF PENNSYLVANIA.

DESIGN FOR A VALANCE FOR WINDOW DRAPERIES OR SIMILAR ARTICLE.

Application filed November 29, 1926. Serial No. 19,876. Term of patent 3½ years.

To all whom it may concern:

Be it known that I, JOSEPH DERK, a citizen of the United States, residing in the city and county of Philadelphia, State of Pennsylvania, have invented the new, original, and ornamental Design for Valance for Window Draperies or Similar Article, of which the following is a specification, reference being had to the accompanying drawing, forming part thereof.

The figure is a plan view of a valance for window draperies or similar article, showing my new design.

I claim:—

The ornamental design for a valance for window draperies or similar article, as shown.

JOSEPH DERK.
